INVENTOR

JOHN OLSON,

By his Attorneys,

Baldwin Wright

UNITED STATES PATENT OFFICE.

JOHN OLSON, OF BATTLE LAKE, MINNESOTA.

BUTTER TUB.

Application filed March 21, 1922. Serial No. 545,450.

To all whom it may concern:

Be it known that I, JOHN OLSON, a citizen of the United States, residing at Battle Lake, in the county of Ottertail and State 5 of Minnesota, have invented certain new and useful Improvements in Butter Tubs, of which the following is a full and clear description.

This invention relates to a container for 10 butter and similar substances and the purpose of the invention is to provide a container which is strong and durable and which will satisfactorily protect the contents thereof.

15 In carrying out my invention I make the container of fibre board or similar fibrous matter. The tub is preferably made of a single piece of such material and the top or cover is also made in one piece, being reinforced, however, by cross pieces or cleats. The bottom of the tub is formed with a flange which is protected with a metal casing and flanged hoops are made to surround the tub at different points.

25 In the accompanying drawings:

Figure 1 shows a side elevation of a butter tub embodying my improvements with the cover applied and locked.

Figure 2 shows a vertical section thereof. 30 Figure 3 is a top plan view of the cover. The tub A is preferably made of fibre board or similar fibrous material formed in one piece. It is preferably frustum shaped, tapering from its upper end downwardly and its bottom portion is formed with a 35 downwardly extending flange a which is surrounded by a metal casing B. At intervals flanged hoops C are applied in the manner clearly shown. The top of the tub instead

of being tapered has a straight or vertical 40 wall portion D adapted to receive the flange e of the cover E.

The cover E is made of a single piece of fibre board or similar material and formed with a downwardly extending flange e adapted to fit on the upper part of the tub. The cover is strengthened by cross pieces or cleats F to which are secured at g wires G, extending down to the top hoop C, which hoop is formed with openings e through which the 50 wires G extend, the wires being twisted at g' after being attached to the hoop.

The tub is preferably glazed, shellacked, or otherwise treated with water-proof material on both the outside and inside and 55 the butter is covered by paper as indicated at H, in order that it may not come in direct contact with the glazed walls of the tub or its cover.

I claim as my invention:

1. A butter tub made of fibrous material strengthened by flanged metal hoops in combination with a cover made of fibrous material strengthened by cross pieces or cleats and connected with one of the hoops by 65 wires.

2. A butter tub made of fibrous material strengthened by a flanged hoop having wire receiving openings in its flange in combination with a flanged cover applied to the top 70 of the tub having cross pieces or cleats for strengthening it and wires secured to the cleats and extending into the openings in the flanged hoop for holding the cover in place.

In testimony whereof, I have hereunto 75 subscribed my name.

JOHN OLSON.
